TUBING COUPLING

Charles S. Crickmer, Dallas, Tex., assignor to
 Merla Tool Corporation, Dallas, Tex., a corpora-
 tion of Texas

Application February 5, 1940, Serial No. 317,373

3 Claims. (Cl. 285—175)

This invention relates to new and useful im-
 provements in tubing couplings.

One object of the invention is to provide an
 improved coupling for releasably connecting tu-
 bular elements together, said device being par-
 ticularly adapted for use in releasably connecting
 a well tubing to a well tool, such as a well packer,
 or the like.

An important object of the invention is to pro-
 vide an improved coupling which includes a pair
 of telescoping elements having co-acting means
 for detachably connecting the same to each other,
 together with a packing means between the ele-
 ments, whereby when the elements are connected
 together, a fluid-tight seal is maintained there-
 between.

A particular object of the invention is to pro-
 vide an improved coupling comprising comple-
 mentary members, one of which is arranged to
 be connected to the lower end of a well tubing
 while the other is adapted to be secured to a
 well packer, and means for detachably connect-
 ing the members to each other, whereby the tu-
 bing may be utilized to set the packer within the
 well, after which the tubing may be disconnected
 and removed from said well without disturbing
 the packer.

Still another object of the invention is to pro-
 vide an improved coupling, of the character de-
 scribed, wherein a fluid-tight seal is maintained
 between the elements of the coupling, the con-
 struction being such that either a mechanically
 distortable packing or a pressure seal packing
 may be employed for providing such seal.

A further object of the invention is to pro-
 vide an improved coupling including a pair of
 telescoping members having a pin, and slot con-
 nection for positively fastening the members to-
 gether and yet permitting detachment thereof
 when desired; the connection being such that it
 does not interfere with the normal function of
 either the packer or tubing, or other elements
 which it may couple.

A construction designed to carry out the inven-
 tion will be hereinafter described, together with
 other features of the invention.

The invention will be more readily understood
 from a reading of the following specification and
 by reference to the accompanying drawing, in
 which an example of the invention is shown, and
 wherein:

Figure 1 is a view, partly in section and partly
 in elevation of an improved coupling, constructed
 in accordance with the invention, and showing

the same connecting a well tubing with a well
 packer.

Figure 2 is an elongate transverse, vertical,
 sectional view of the coupling.

Figure 3 is a horizontal, cross-sectional view,
 taken on the line 3—3 of Figure 2, and

Figure 4 is a view, similar to Figure 2, showing
 a modified form of the device.

In the drawing, the letter A designates a well
 packer which may be of any desired construction
 and which may be purchased on the open market.
 As illustrated, the packer includes an elongate
 tubular mandrel 10 having a flanged cap mem-
 ber 11 threaded, or otherwise secured thereto.
 The cap member is formed with an annular re-
 cess 12 within which the upper reduced end of
 a packing element or sleeve 13 is confined and
 said sleeve is constructed of rubber, rubber com-
 pound, or other elastic material. The lower end
 of the sleeve 13 is also reduced and is confined
 within a recess 14 which is formed within a
 thimble or cone 15, this latter member being
 slidable on the mandrel 10, and being normally
 supported on an external shoulder (not shown)
 formed on the mandrel 10.

A plurality of gripping slips 16 are slidable
 vertically on the inclined outer surface of the
 cone 15 and are carried by a plurality of spring
 members 17. The lower portions of the spring
 members 17 are bowed outwardly so as to engage
 the wall of the well casing C, through which the
 packer is adapted to be lowered. The extreme
 lower ends of the springs 17 are suitably secured
 within a ring 18 which is adapted to rest upon
 the upper edge of a coupling collar 19 secured
 to the lower end of the mandrel 10. The upper
 portions of the springs 17 are confined within,
 and secured to a ring 20, which ring is formed
 with a depending hook 21. This hook is adapted
 to engage a radially extending pin 22 which is
 provided on the mandrel 10 and when so engaged,
 the slips are locked against movement relative to
 the mandrel and to the cone 15 carried by said
 mandrel.

When it is desired to set the packer, the man-
 drel 10 is raised and then rotated so as to disen-
 gage the pin 22 from the hook 21, the slip as-
 sembly 16 being held stationary at such time, due
 to the frictional engagement of the springs 17
 with the wall of the casing C. After the pin 22
 has been disengaged from the hook, the mandrel
 may be lowered relative to the slip assembly.
 Such lowering of the mandrel causes the cone 15
 to move downwardly between the slips 16 to move
 said slips radially outward into engagement with

the casing wall. The engagement of the slips with the casing wall arrests further downward movement of the cone 15 and a continued downward movement of the mandrel 10 forces the packing element or sleeve 13 into a distorted or expanded position, whereby said sleeve packs off between the mandrel 10 and the casing C. It is pointed out that this type of packer is of the usual construction and the details of its assembly form no part of the present invention. The packer and its operation have been described merely for the sake of clarity.

The coupling collar 19 at the lower end of the mandrel 10 is arranged to be coupled to an anchor tube B. The cap member 11 which is secured to the upper end of the mandrel 10 is extended upwardly to form a tubular fishing neck 11a and this neck is internally screw-threaded (Figure 2) to receive the reduced lower end of a tubular extension or sleeve 23. The upper portion of the sleeve or extension is provided with a pair of diametrically opposed J-slots 24, one of which is clearly shown in Figure 1. Each J-slot is provided with a vertical portion 24a which extends downwardly from the upper edge of the sleeve and also has a horizontal or laterally extending portion 24b. At the inner end of the lateral portion 24b, a vertical recess 24c is formed. Thus, it will be seen that the tubular extension or sleeve 23 is secured to and forms a part of the packer assembly A.

For releasably connecting the packer assembly to the well tubing string T, the lower end of said string is provided with an elongated tubular mandrel or coupling element 25. This element is arranged to be inserted within the tubular extension 23, as is clearly shown in Figure 2, said element being provided with diametrically opposed, radial pins 26 which engage within the J-slots 24 to couple the mandrel 25 to the extension. Manifestly, the bore 25a of the mandrel 25 forms a continuation of the bore of the tubing string T and also communicates with the bore of the packer assembly A through the extension 23, whereby an unrestricted flow through the tubing may occur. It is apparent that the pins 26 and J-slots 24 provide a detachable and releasable connection between the mandrel 25 secured to the tubing and the extension 23 carried by the packer.

For packing off between the mandrel 25 and the bore of the extension 23 when these parts are coupled together, the lower end of the mandrel is reduced and an annular packing cup 27 is mounted thereon. An inverted packing cup 28 is disposed below the packing cup 27 and both cups are mounted on a confining member or sleeve 29 which is threaded into the lower end of the mandrel. The sleeve 29 is formed with an external shoulder 30 whereby the packing cups 27 and 28 are clamped between said shoulder and the lower end of the mandrel. By observing Figure 2, it will be seen that the lips of the packing cups 27 and 28 are directed in opposed relation, whereby a fluid-tight seal in either direction is provided.

In the operation of the device, the parts of the packer assembly A are in the position shown in Figure 1 with the hook 21 engaged with the pin 22, whereby the slips 16 are held in a retracted position at the lower end of the cone 15. The mandrel 25 which is connected to the lower end of the tubing T is inserted within the bore of the extension 23, with its radial pins 26 engaged within the recess 24c of the J-slots 24. The

packer may thus be lowered into its proper position within the well casing by means of the tubing T.

When the position at which it is desired to set the packer A is reached, the tubing is lifted a slight distance so as to lift the extension 23 and mandrel 10 of the packer assembly A, after which said tubing is rotated to rotate said sleeve and mandrel 10. Such lifting and rotation of the mandrel 10 of the packer causes the pin 22 on said mandrel to disengage the hook 21 of the slip assembly. The slip assembly is, of course, held stationary during such movement of the mandrel by means of the frictional grip of the springs 17 with the casing wall. After the pin 22 is disengaged from the hook 21, the mandrel 10 is lowered so as to cause the cone 15 to expand the slips 16 into their gripping position. A continued lowering of the mandrel by means of the tubing T results in a distortion of the packing element 13, whereby the annular space between the tubing T and casing C is accomplished. The packer A is thus set by means of the tubing T and the parts may remain in this position as long as desired. A flow may occur upwardly through the anchor tube B and then through the packer A, through the extension 23, coupling member or mandrel 25 and then upwardly through the tubing string. The provision of the packing cups 27 and 28 within the extension 23 prevent any escape of fluid from the upper end of the extension and thus the flow upwardly is directed through the tubing string.

If, for any reason, it is desired to remove the tubing, without disturbing the packer, this may be readily accomplished by merely lowering the tubing and its mandrel 25 with relation to the elongate extension or sleeve 23. Such lowering is possible because the sleeve is locked against downward movement since it is carried by the packer assembly A. Lowering of the tube moves the pins 26 on the mandrel or coupling member 25 downwardly into the lateral portions 24b of the J-slots. Upon reaching such position, the tubing may be rotated to move the pins 26 into alignment with the vertical portions of the J-slots 24, after which the tubing may be pulled upwardly and entirely removed from the casing without disturbing the packer. The packer may remain in the well casing for any length of time and whenever it is desired to remove said packer, it is only necessary to again lower the tubing, connect the pins 26 with the slots 24 of the extension or sleeve 23 and then re-engage the pin 22 of the packer mandrel 10 with the hook 21 of the slip assembly. In this manner, the packer could be removed at any desired time.

If it is not desired to return the tubing into the well casing in order to retrieve the packer assembly, a suitable fishing tool or overshot (not shown) may be lowered on a wire line or cable and may be engaged with the fishing neck 11a on the upper end of the cap 11. An upward pull on this cap element results in a raising of the mandrel and of the cone 15 relative to the slips, whereby said slips may move into a disengaged position. The packer may then be removed by pulling the same upwardly to the surface.

From the above it will be manifest that a simple and effective means for positively coupling the tubing and packer assembly to each other is provided. When positively connected, the tubing may be utilized to set the packer in a desired position within the well casing, after which the tubing may be readily removed without disturb-

ing said packer. The tubing may also be utilized for removing the packer at any time.

The invention is not to be limited to the use of the pressure seal packing cups 27 and 28, shown in Figure 2, as there are various other methods of packing off between coupling elements 23 and 25. In Figure 4 a slightly modified form of packing element for this purpose is shown. As illustrated, the lower end of the mandrel 25 is provided with an extension 25b. An annular flange 31 is formed at the upper end of the extension and the space between this flange and said extension provides an annular recess 32. The reduced upper end of an elastic packing collar or sleeve 33 is confined within this recess. The lower end of the packing element is disposed within a recess 34 which is provided at the upper end of a ring or collar 35 which is slideable on the extension 25b. The collar 35 is connected to the extension through a slot 36 and pin 37.

In this form of the invention the sleeve 23 is sharply reduced near its lower end to provide an internal seat 38 and this seat is adapted to engage the lower end of the collar 35. In the operation of this form, the packing element 33 is normally in an undistorted position with the collar 35 on the extreme lower end of the extension. When the mandrel 25 is inserted within the extension 23, the lower end of the collar strikes the seat 38, whereby further downward movement of the collar is arrested. This occurs prior to the time that the pins 26 reach the lateral portions 24b of the J-slots 24. A continued downward movement of the mandrel 25, moving the pins 26 into said lateral portions, results in the weight of the mandrel and tubing being placed on the packing element 33, thereby distorting said packing element into the position shown in Figure 4. In such position, a fluid-tight seal between the extension 23 and the mandrel 25 is obtained. In both forms of the invention, a releasable connection between the tubing and the packer is effected.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A coupling for releasably connecting a pair

of tubular members including, an elongate sleeve secured to one of the members and having an internal seat therein, a tubular mandrel secured to the other member and insertable within the sleeve, means for detachably coupling the mandrel to the sleeve, a packing element surrounding the mandrel, and a retaining collar slideable relative to the mandrel for confining the packing element on said mandrel, said collar being adapted to engage the seat to permit the mandrel to move downwardly relative thereto during the coupling operation to distort the packing element into sealing position.

2. A coupling for releasably connecting a pair of tubular members including, an elongate sleeve secured to one of the members and having an internal seat therein, a tubular mandrel secured to the other member and insertable within the sleeve, means for detachably coupling the mandrel to the sleeve, a packing element surrounding the mandrel, a retaining collar surrounding the mandrel below the packing element, and a slot and pin connection between the collar and mandrel to permit limited movement of these parts with respect to each other, said collar being arranged to engage the seat when the mandrel is inserted into the sleeve, whereby after such engagement the mandrel may continue a limited downward movement with respect to the collar to distort the packing element into sealing position.

3. A coupling for releasably connecting a pair of tubular members including, an elongate sleeve secured to one of the members and having an internal seat therein, a tubular mandrel secured to the other member and insertable within the sleeve, means for detachably coupling the mandrel to the sleeve, a packing element surrounding the mandrel, a retaining collar surrounding the mandrel below the packing element, a slot and pin connection between the collar and mandrel to permit limited movement of these parts with respect to each other, said collar being arranged to engage the seat when the mandrel is inserted into the sleeve, whereby after such engagement the mandrel may continue a limited downward movement with respect to the collar to distort the packing element into sealing position, the detachable coupling means being so located on the mandrel and sleeve that the same cannot be engaged until after the packing element is distorted.

CHARLES S. CRICKMER.
